UNITED STATES PATENT OFFICE.

JOHN W. JONES, OF ROOSEVELT, OKLAHOMA.

VENTILATING SYSTEM.

968,854.

Specification of Letters Patent. Patented Aug. 30, 1910.

Application filed October 3, 1908, Serial No. 455,986. Renewed December 8, 1909. Serial No. 532,033.

To all whom it may concern:

Be it known that I, JOHN W. JONES, citizen of the United States, residing at Roosevelt, in the county of Kiowa and State of Oklahoma, have invented certain new and useful Improvements in Ventilating Systems, of which the following is a specification.

This invention comprehends certain new and useful improvements in ventilating systems of that type which operate upon the plenum principle and are designed to prevent the air in the various rooms or parts of a building from becoming vitiated, by continually forcing a fresh supply of air therein, without causing any drafts in the rooms, as would be dangerous or annoy the occupants thereof, and the object of the invention is an improved apparatus of this character which is most efficient in operation and which is simple and durable in construction and may be conveniently installed at a minimum cost.

With this and other objects in view that will more fully appear as the description proceeds, the invention consists in certain constructions and arrangements of the parts that I shall hereinafter fully describe and then point out the novel features thereof in the appended claim.

For a full understanding of the invention and the merits thereof, and to acquire a knowledge of the details of construction, reference is to be had to the following description and accompanying drawing, in which:

Figure 1 is a cross sectional view of a building equipped with my improved ventilating system; and, Fig. 2 is a detail view of the fan, showing the form of screened intake employed when the fan is located on the exterior of the building.

Corresponding and like parts are referred to in the following description and indicated in all the views of the drawings by the same reference characters.

In carrying out my invention, I provide a blast fan 1 which may be of any desired or approved construction or design and which may be turned by any suitable motor (not shown), the fan being placed without the building, or being located in any position found most convenient or desirable in practice, although preferably upon the roof, as shown. This fan 1 is provided with a sup-

ply of fresh air by means of an intake 2 which establishes communication between the exterior of the building and the interior of the fan, and which is preferably screened, as indicated at 3, for a purpose to be herein-after disclosed. From the fan 1, fresh air is forced through a main supply pipe or air duct 4 which extends into the various rooms or parts of the building to be ventilated, one or more distributing pipes 5 leading from the main supply pipe 4 in each room of the building, and being preferably perforated, as indicated at 6, so as to provide means of escape for the fresh air. In practice, it has been found desirable to locate these distributing pipes near the ceilings of the rooms.

Attention is particularly directed to the fact that the perforations or outlets are arranged in two longitudinal series, the said series being positioned diametrically oppositely to each other and being disposed in a vertical plane. The distributing pipes are otherwise imperforate. By virtue of such a construction fresh air escaping through the perforations of the lower series is directed vertically downwardly into the room, while the air passing through the upper perforations is directed against the ceiling and is deflected laterally thereby, so as to be distributed effectually to all parts of the room.

From the foregoing description, in connection with the accompanying drawing, it will be apparent that I have provided an improved ventilating system by means of which fresh air may be supplied to the various rooms of a building, near the ceilings of the same, so as to forcibly eject or exhaust any foul air collected in the rooms and maintain proper sanitary conditions in the same, said ventilating apparatus being simple and durable in its construction, and consisting of comparatively few parts that may be easily and cheaply manufactured and readily installed in a building. Inasmuch as the intake is screened, as indicated at 3, the admission of any foreign substances, such as dust or bugs or the like to the interior of the blast fan, is effectually precluded, and this manifestly prevents the possibility of the fan becoming clogged with such particles, or the liability of the latter being forced through the air ducts and discharged into the various rooms of the building.

Having thus described the invention, what I claim is:

The combination with a building, of a ventilating system of the character described comprising a fan mounted on the roof of the building and provided with a screened intake to exclude foreign particles, a fresh-air supply pipe having connection with the fan and extending downwardly through the floors of the building, and distributing pipes connected to the supply pipe and leading therefrom into the respective rooms on each floor, the distributing pipes being arranged in proximity to the ceilings of the rooms and being imperforate with the exception of upper and lower longitudi-

dinal series of outlets extending therethrough at diametrically opposite points, the series of outlets of each distributing pipe being disposed in a vertical plane, the lower outlets directing the fresh air vertically downwardly into the room and the upper outlets directing the fresh air against the ceiling of the room, whereby the air is deflected laterally by the ceiling to insure of the thorough distribution thereof.

In testimony whereof I affix my signature in presence of two witnesses.

JOHN W. JONES. [L.S.]
